UNITED STATES PATENT OFFICE.

STILLMAN AUGUSTUS MOULTON, OF SAN JOSÉ, CALIFORNIA.

CULTIVATOR.

SPECIFICATION forming part of Letters Patent No. 325,432, dated September 1, 1885.

Application filed May 27, 1885. (No model.)

To all whom it may concern:

Be it known that I, STILLMAN A. MOULTON, a citizen of the United States, residing at San José, in the county of Santa Clara and State 5 of California, have invented a new and useful Improvement in Cultivators, of which the following is a specification, reference being had to the accompanying drawings.

My invention relates to an improvement in 10 cultivators adapted especially for use in orchards; and it consists in the peculiar construction and combination of devices that will be more fully set forth hereinafter, and particularly pointed out in the claims.

15 In the drawings, Figure 1 is a side elevation of a cultivator embodying my invention, with the near wheel removed. Fig. 2 is a top plan view of the same. Fig. 3 is a front elevation.

The frame A of the cultivator consists, es- 20 sentially, of the transverse beams B and C and the longitudinal connecting-beams D.

E represents brackets that are secured to the inner side at the center of the beams C, their securing-bolts passing through slots e 25 that are made in the brackets. Similar slotted brackets, F, are secured to the upper side at the center of the front beam, B.

G represents a tongue, the rear end of which is bolted between the brackets E and F. By 30 reason of the slots in the brackets the tongue may be adjusted laterally to either side of the center of the frame, as will be very readily understood.

H represents a bar that is hinged to one of 35 the beams B, and on the upper side of this bar is secured a sliding bracket, I, having slots K, through which its securing-bolts L pass, and formed with this bracket is a segmental rack, M. A similar sliding bracket, N, hav- 40 ing slots O, is secured on the opposite beam, B, by means of bolts P, and near the center of this bracket, in the forward portion thereof, is a vertical slotted standard, R. A curved 45 rack, S, is formed with the rear end of the bracket N, and at the front end of said bracket is a pivotal lug, T.

U represents a double-cranked axle, which is journaled in the bracket I, and in the slotted standard of the bracket N. A hand-lever, 50 V, is secured near one end of this axle, and engages with the segmental rack M.

A hand-lever, W, is pivoted in the stud T

on the opposite side of the frame, is fulcrumed to the axle U, and engages with the curved rack S.

55

The supporting-wheels are journaled on the ends of the axle.

The rear beam, C, has its ends extending beyond the beams D, and on the under sides of these projecting ends are bolted keepers X, 60 which are arranged diagonally, and are adapted to secure the inner ends of diagonal forwardly-projecting removable arms Y, on the outer ends of which are journaled removable circular disks or rollers Z, which are provided 65 with cushioned rims.

Cultivator-teeth of any suitable construction are secured to the beams B C D and to the arms Y, as shown. From the upper side of the tongue G, above the front beam, B, projects a headed stud, A', and similar studs, B', 70 project from the upper side of the beam B on opposite sides of the tongue. C' represents a driver's seat, the standard of which is provided with an opening, D', at its foot large 75 enough to receive the heads of the studs A' and B', and from the front side of this opening extends an open slot, E', of a corresponding diameter to the shanks of said studs. By means of this construction the driver's seat 80 may be placed either at the center of the frame, on the stud A', or upon either side thereof, upon the studs B', as will be very readily understood.

By providing the sliding brackets in which 85 the axle is secured, the axle may be moved at an angle to the cultivator-frame for the purpose of changing the line of the wheels and enabling the cultivator to run close to the trees and to draw to one side, thus overcom- 90 ing the side draft of the cultivator-teeth se- cured to the inner side arm, Y, when only one of said side arms is used. The purpose of the hinged bar H and the slotted standards of the bracket N and the hand-lever W is to 95 enable the frame to be inclined, and thereby cause the teeth on the outer side of the frame to run deeper in the ground than those on the inner side thereof when it is necessary to cause the inner teeth to run shallow in the 100 ground in order to avoid disturbing the roots of the trees. The removable arms Y enable the cultivator-teeth to be extended so as to work under the branches of the trees where

the cultivator-frame could not be driven, and the cushioned disks on the ends of said arms are to prevent abrasion of said arms with the trunks of the trees, and thereby prevent injury to the latter. The hand-lever V and the cranks on the axle enable the cultivator-teeth to be raised entirely out of the ground when not at work, or to be lowered to any desired extent in the ground.

10 Having thus described my invention, I claim—

1. In a sulky-cultivator, the extending arms Y, having the cultivator-teeth, and the disks at their outer ends for preventing abrasion of the trees, substantially as described.

15 2. The combination, in a sulky-cultivator,

of the frame A, the bar H, hinged thereto at one side, and the sliding bracket on said bar, the sliding bracket N on the opposite side of the frame, and having the slotted standard, 20 and the axle secured in the slotted standard and in the hinged sliding bracket, and the lever W for raising or lowering the free end of the axle, substantially as described.

In testimony that I claim the foregoing as my 25 own I have hereto affixed my signature in presence of two witnesses.

STILLMAN AUGUSTUS MOULTON.
